UNITED STATES PATENT OFFICE.

LAURENCE E. McDONOUGH, OF CHICAGO, ILLINOIS, ASSIGNOR TO MAXANT BUTTON AND SUPPLY COMPANY, OF CHICAGO, ILLINOIS, A CORPORATION OF ILLINOIS.

PEDAL-OPERATED PRESS.

Application filed October 30, 1926. Serial No. 145,303.

The purpose of this invention is to provide an improved construction of a nature of a pedal operated press of the general character common for light die and press work such as 5 button making, particularly adapted for accommodating the limbs of the operator in the swinging movement of the pedal, and providing a seat for the operator hinged to the press frame for swinging to adjust the position of the seat to the operator's convenience in view of the pedal movement, and at the same time rendering the seat stable in position as adjusted for thus accommodating the operator. It consists in the elements and features of construction shown and described as 15 indicated in the claims.

In the drawings:—

Figure 1 is a plan view of a press and connected operator's stool embodying this invention.

Figure 2 is a side elevation of the same.

The structure shown in the drawings comprises a die press which is in general of familiar construction comprising the standard 25 A upon which is mounted the press proper, B, having the reciprocating head, B¹, actuated for working stroke by the lever, B², which is connected for deriving its operating movement by means of a link B³, which is connected 30 for actuation by the pendulous pedal member, C. One characteristic of the invention consists in the form of this pendulous pedal member which, being fulcrumed at its upper end on the press standard, A, as indicated at 35 c, is formed with a rearward bend at about one-third of its length downward from its fulcrum at c, as seen at C¹, the pedal terminal or foot rest, C², being upturned from the lower end of said pendulous member, and the 40 operating link, B³, being pivotally connected at its lower end to the pendulous pedal substantially opposite the bend, C¹, where a forked lug is provided as seen at c¹. It will be clear that the pendulous lever being fulcrumed at c and pivotally connected at c¹ to the 45 lower end of link, B³, is, in effect, a bell crank lever for transmitting the operating motion at right angles. The purpose of this bend in the pendulous pedal will be understood to be 50 to accommodate the knee of the operator, so that the operator may be positioned close to the press without being obliged to swing the knee aside to avoid collision with the pendulous pedal in the forward swinging movement, or as the only alternative, adjusting 55

the seat at such distance back from the press as to compel the operator to bend over forwardly in order to be in a position to observe the work.

In conjunction with the press having this 60 knee-bent pendulous pedal, it is desirable to mount the operator's seat on the pedal frame so that it may be adjusted back and forth with respect to the frame, and also vertically to accommodate the operator in respect to length 65 of limb and other proportions. Heretofore it has been proposed, to hinge the operator's seat to the press standard for swinging horizontally to afford such adjustment; but such construction as heretofore proposed, is objectionable particularly in connection with 70 a pendulous pedal, because the operating movement of the pedal being away from the operator, tends to swing the operator's seat back from the press and requires re-adjustment by the effort of the operator after each 75 pedal stroke. This objection to the hinged and swinging seat is overcome in the construction shown which comprises the swinging seat bracket, E, pivoted vertically for 80 horizontally swinging to the fixed bracket, F, bolted in a fixed position to the press frame, A, the seat, G, having its spindle, G¹, mounted for vertical adjustment in the end of the 85 swinging bracket, E, said swinging bracket being provided with a leg, H, of proper length to rest upon the floor upon which the press frame stands. It will be recognized that with this construction the weight of the operator upon the seat tends to hold both the 90 seat and the press frame firmly positioned on the floor against any tendency of movement of either the seat or the press, which might otherwise result from the operating stroke of the pedal by the thrust of the operator's 95 foot forward, that is, away from the seat.

In order to afford some range of adjustment to accommodate the length of limb and other bodily proportions of the operator and permit variation according to the preference 100 of the operator in respect to position of the arc through which the operator's foot resting on the pedal swings in actuating the press, the link, B³, is provided with a plurality of pivot holes, 10, at short distances apart, and the fork lug, c¹, has also a plurality of pivot holes, 105 12, at short distances apart, and within limits any pivot hole, 10, may be registered with any pivot hole, 12, for receiving the pivot bolt, thereby permitting a very considerable choice 110

as to position of the arc in which the pedal will swing,—that is, whether nearer to or farther from the seat. And similarly, to accommodate the length of limb of the operator, the seat bracket, E, is arranged for attaching the seat G adjustably by means of a T-fitting, K, which has a horizontal stem for insertion through a horizontal socket or aperture in the bracket, E, the cross, K¹, of this T-fitting being bored to receive the seat spindle, G¹, and set screws, 20 and 21, being provided for respectively securing the stem of the seat at vertical adjustment in the T-fitting and securing the stem of the T at horizontal adjustment in the bracket arm, E.

15 I claim:—

In a foot-operated machine, a standard, a

pendulous operating lever fulcrumed at its upper end on the standard and having a pedal at the lower end, said lever having a wide angular bend between its fulcrum and the pedal positioned to accommodate the operator's knee, and having means at said bend providing pivotal connection with a vertically movable operating member for actuating a machine on the standard, whereby said lever operates as a bell crank to transform its pendulous swinging motion into vertical reciprocation.

20 In testimony whereof, I have hereunto set my hand at Chicago, Illinois, this 5th day of October, 1926.

LAURENCE E. McDONOUGH.
